UNITED STATES PATENT OFFICE.

FRED LERCH, OF VIRGINIA, MINNESOTA.

MECHANICAL SHOVEL.

1,307,448.

Specification of Letters Patent. Patented June 24, 1919.

Application filed March 20, 1917. Serial No. 155,994.

To all whom it may concern:

Be it known that I, FRED LERCH, a citizen of the United States, residing at Virginia, in the county of St. Louis and State of Minnesota, have invented certain new and useful Improvements in Mechanical Shovels, of which the following is a specification, reference being had therein to the accompanying drawing.

10 This invention consists of certain new and useful improvements in mechanical shovels and relates particularly to that class of shovel used in connection with tunneling machines for work in underground mining, 15 such as for iron ore, coal, and the like.

In such mining, the question of space in which to work is a very essential factor, and the object of my present invention is to provide a machine of this character especially adapted to such restricted working quarters.

Another object is to provide a shovel of this character especially designed for quick and positive action, and one having the 25 maximum range of action in the limited working quarters referred to.

Another object is simplicity of operation and construction, and

Other objects will appear in the further 30 description of the invention.

In the accompanying drawings forming part of this application, and in which like reference characters indicate like parts:

Figure 1 is a side elevation of my improved mechanical shovel, mounted upon a vehicle.

Fig. 2 is a front end elevation with the shovel in its uppermost position.

Fig. 3 is a top plan view of Fig. 1.

40 Fig. 4 is a fragmental vertical sectional view of a modified form of dipper arm support, and

Fig. 5 is a side elevation of Fig. 4.

As is well known in the art, the office of such a machine is to work upon the face of the tunnel and convey the mined material or muck to a tram car or cars in the rear of the machine, the machine itself being mounted upon a wheeled vehicle or chassis.

50 I am aware that machines of this character have heretofore been employed for a like purpose, they being usually pivotally mounted upon a carriage and designed to discharge the mined material from directly overhead with respect to the machine; therefore this overhead discharge feature

and that of being mounted upon a turn table on a carriage does not constitute a novel part of my invention, as neither does the peculiar manner of applying a motor 60 to the device.

1 represents the body of the carriage mounted upon wheels 2 which are of a like gage to that of the regular tram track and travels thereupon. 3 represents the platform upon which the shovel and its coöperating mechanism is supported and which platform is pivotally mounted in any desired manner upon the body 1 of the carriage, thus acting as a sort of turn table 70 and may be made mechanically or manually operative in any desired manner.

Upon either side of the platform 3 is rigidly fixed an upright slightly truncated A-frame 4, they being suitably transversely braced in any desired manner to form a strong rigid supporting frame, and I prefer to construct these A-frames chiefly of small channel bar iron. Mounted within the upper truncated ends of the A-frames, 80 are two parallel transverse shafts 5 and 6 spaced apart and each loosely carrying in the center thereof, a deep flanged sheave 7, the latter being alined with each other, and designed to alternately engage the dipper hoisting line 8.

Within the truncated end of each A-frame and upon the outside thereof, is pivotally supported, as at 9, a depending pendulum lever arm 10 each of which is pivotally attached at its free end, as at 11, to one of the upwardly arched dipper sticks or arms 12, the latter in turn rigidly supporting intermediate their ends as at 13, the scoop-shaped dipper 14. The dipper 14 is formed with a flat bottom, right angled sides, and slightly transversely convexed, scoop-shaped end, the cutting edge of which is rounded outwardly.

The dipper rope 8 which is attached centrally to the uppermost edge of the flat bottom of the dipper 14 leads over one of and between the sheaves 7-7 and to a suitable winding drum operated and controlled in any desired manner.

To the legs of each A-frame and near the lower ends thereof is rigidly fixed a quadrant member 19, having a slot 20 therein through which projects a guiding bolt 21 attached to the pendulum arm 10 and which acts as a lateral guiding member for said arm. Just below this guide connection is

- attached as at 15 to each pendulum arm one side of a sprocket chain 22 which is endless and passes around a sprocket wheel 23 at the foot of each leg of the A-frame. To 5 compensate for the raising and lowering of the ends of the arms 10 in relation to the chain 22 as they swing back and forth, a vertical slot is formed in the arm through which the attaching bolt 15 extends, thus 10 preventing abnormal tension upon the chain by the reciprocation of the arms. Each transverse pair of these sprockets is fixed to a cross shaft 24 journaled in the feet of the A-frames and one or both of which shafts 15 may be directly connected to the driving mechanism, not shown. I have illustrated a spur gear 25 upon one of the shafts for this purpose and any suitable motive power may be employed. 20 By this attachment the free ends of the pendulum arms may be swung from one side to the other of the A-frames, simultaneously or held at any desired point there-between during the manipulation of the shovel. 25
- Adjacent the foot of the front leg of each A-frame 4 is fixed a small angle plate bracket, 16, in which is mounted a transverse shaft or rod 17. Upon this rod is pivotally 30 supported the inverted U-shaped member 18 which has rigidly fixed to the center thereof an arm 37, carrying in the outer bifurcated fabricated terminus 38 an elongated sheave or roller 39. 35 The purpose of the line brace thus formed is to produce a more direct upward draft upon the dipper and the brace being pivotally supported upon the machine is made to travel with the dipper in the following manner: 40
- A depending extension 40 is formed upon each of the shaft engaging legs of the U-shaped member and carry fixed in their free ends a transverse shaft or rod 41 which is 45 sufficiently long to have its ends engaged by the under side of the dipper arms 12 and which engagement, as is evident, controls the throw of the line brace at such times as when the line 8 bears upon the roller 39 in 50 the brace. The angle of the depending extension 40 to the brace is such as will prevent the brace descending below an angle of 45 degrees to the base thereof. 55
- Counter weights 42 are attached in any desired manner to the legs of the U-shaped member 18 and which weights tend normally to keep the brace back against the front of the A-frames and to keep it from falling forward when the dipper arms are 60 free from engagement with the shaft 41, as for example, when discharging its burden. 65
- Any desired form of spiral or other spring or springs such as illustrated at 31 and attached to the buffer, may be employed for this purpose in lieu of the counter weights,

if preferred. The automatic positioning of the brace may be accomplished in any desired manner if preferred.

Thus it will be seen that when the dipper is lowered forward to engage the material 70 being shoveled, the arms 12 will contact the ends of the shaft 41, counteract the influence of the counter weights 42 and result in carrying the line brace along after the dipper and cause it to assume a position similar 75 to that shown in Fig. 1, which causes the line 8 to feed over the roller 39. When the dipper is thrown up over the A-frames, the combined influence of the line, the dipper 80 and the counter weights or any one of them independently will throw the line brace back to its inactive position against the A-frames. 85

Now assuming the dipper line 8 being led to a suitable drum 26 and controllable therefrom, it is evident that any desired position 90 of the dipper within or between the various arcuate paths indicated in dotted lines Fig. 1, may be readily assumed, and co-operative action of the pendulum arms with the hoisting line will result in as near human effect 95 upon the shovel as it seems possible to produce by mechanical means.

By this means the dipper has a maximum horizontal throw of approximately the 95 length of the carriage from each end thereof which provides all the scope necessary for proper shoveling and loading of the tram cars.

As a means for quickening the action of the shovel and at the same time lessening the 100 throw thereof, I provide a buffer member comprising the upright laterally offset members 27-27 pivoted as at 28 to the two rear legs of the A-frames and the cross bar 29 rigidly fixed thereto. This buffer frame is 105 held normally against the bumper bar 30 by suitable tractive spiral or other springs 31-31 attached at one end to the buffer frame and at the other to the respective A-frames by being hooked over suitable projecting pins 50 upon the inside of the A-frames and of which there may be a number to admit of longitudinal adjustment of the springs 31. The upper free ends of the members 27-27 extend within the path of 110 the protruding ends of the buffer cleat 32 fixed to the open end of the flat bottom of the dipper when it approaches the point of discharge. 115

When thus suddenly engaged by the dipper 120 per the buffer will yield with it for a short distance, but the shock having started the load in the dipper, by its momentum, in advance of the latter, the tractive effect of the springs 31-31 will tend to stop the dipper 125 and free it entirely from its load. This being done, draft upon the dipper line 8 will quickly start same on its return trip, thus shortening the travel of the dipper and increasing the efficiency of the device. 130

It is to be understood that a slow steady pull upon the dipper rope would not permit the dipper to pass the central point of support above the pivot 9. The momentum of 5 the shovel will normally assist in carrying it over this point when traveling in either direction and together with the ability to shift quickly the pivotal point 11 of support at the ends of the pendulum arms and pass 10 it back of the center of gravity of the load in the dipper will effectually assist in passing this point of extreme height and that, when desired, with considerable force. As 15 the dipper passes the point of highest travel above referred to, the rope 8 will shift from one sheave 7 to the other as is evident and the same direction of pull on the same rope serve to operate the dipper in either direction alternately.

20 It is evident that the buffer may be dispensed with entirely if preferred and in which event, the dipper may be passed entirely over the car being loaded and the buffer cleat 32 on the dipper allowed to strike 25 the edges of the car to effect a clean unloading of the dipper, the dipper arms passing upon either side of the car.

In Figs. 4 and 5 I have illustrated a modified form of support for the carriage end of 30 the dipper arms 12 which consist of grooved wheels 33 operating between the webs of two vertically opposed T-tracks 34—34, a pair of which being fixed longitudinally each side of the platform 3. These grooved wheels are 35 fitted with a wrist pin 35 upon which the ends of the dipper arms are pivoted and the opposite side of the wheel has a pin 36 to which the sprocket chain 22 is attached and which chain imparts horizontal reciprocating 40 motion to the wheels 33, thereby affording substantially the same movement of the inner end of the dipper arms as that of the pendulum arm connection, though less graceful or effective, as the travel is entirely 45 horizontal.

In the use of such machines it is customary to provide suitable means for quickly attaching the carriage upon which the machine is mounted to the tram track and for 50 such purpose I have illustrated at 36 a convenient hand operated gripping means, but which does not constitute a novel part of my present invention.

The dipper arms 12—12 are arched as 55 illustrated to prevent the same engaging the forward corners of the carriage platform, when swinging to one side and shoveling abnormally deep. It will also be seen that when the pendulum arms 10—10 are upon 60 either side of a central vertical position, the pivotal point 11 will be proportionately elevated, thus further assisting in deep digging without engaging the corners of the carriage and presenting the cutting lip of

the dipper at the most desirable angle for 65 satisfactory work.

While I have shown the dipper as being the full width of the machine, it is evident that the same may be of less width if found more desirable and various other modifications within the scope of the invention may be resorted to without departing from the spirit thereof.

From the foregoing it is evident that I have devised a mechanical shovel having 75 novel action and one admirably adapted to the work intended. The action of a single line capable of throwing the dipper in either direction together with the automatic changing of the direction of draft of the line at the time of greatest stress thereupon and the arched dipper arms to increase the scope of action, assist materially in producing such desired results.

Having thus described my invention what I claim and desire to secure by Letters Patent, is:

1. In combination with a suitable portable support, an upstanding A-frame fixed to 90 either side of the support and centrally thereof, a depending arm pivoted in the apex of each frame, a dipper stick pivoted to the free end of each arm and extending beyond the end of the platform, a dipper carried intermediate the free ends of the sticks, a controlling line leading from the dipper to a point intermediate the apexes of the A-frames for raising and lowering the dipper to or from either side of the A-frames 95 and means for simultaneously controlling the free ends of the arms for extending the dipper sticks longitudinally and for shifting the central support of the dipper for throwing it to one side or the other of the apexes 100 of the A-frames, as the dipper is manipulated thereover.

2. In combination, a suitable portable support, a dipper pivotally carried by the support and operating thereover, a single 110 line for raising and lowering the dipper upon either side of the support, means for automatically changing the direction of draft of said line and means for reciprocating the point of pivotal support of the 115 dipper.

3. The combination with a suitable support of depending pendulum-like arms pivotally mounted in the upper end of the support and adjustable to either side of a vertical line with said pivotal point, dipper sticks pivotally attached to the free ends of the arms, a dipper rigidly fixed intermediate of the opposite ends of the sticks, a single line attached to the dipper and leading through the upper end of the support and means adjacent the free end of the pendulum-like arms for operating same.

4. A shoveling device of the class de-

scribed, comprising a support consisting of two spaced A-shaped frames, depending pendulum-like arms pivotally mounted in the upper end of the frames and adjustable to either side of a vertical line with said pivotal point, dipper sticks pivotally attached to the free ends of the arms, a dipper rigidly fixed intermediate of the opposite ends of the sticks, means for raising and lowering the dipper over the support, and means for swinging the free ends of the pendulum arms.

5. The combination with a structure as described in claim 4, of the means for operating the free end of the pendulum-like arms being mounted within the base of the A frames and an arcuate slotted guide-way to prevent lateral movement of the arms.

6. The combination with a structure as described in claim 4, of two oppositely disposed sheaves journaled within the upper end of the A-shaped frames and means for raising and lowering the dipper comprising a single line operative intermediate of the two sheaves whereby the dipper may be operated upon either side of the pivotal point of the pendulum-like arms.

7. A mechanical shoveling device of the class described including a suitable support consisting of two substantially A-shaped frames, one upon each side of a platform, two parallel cross shafts journaled in the apexes of the A-frames, opposed sheaves loosely mounted upon the shafts, depending pendulum-like arms pivotally mounted in the upper end of the frames, and adjustable to either side of a vertical line with said pivotal point, dipper sticks pivotally attached to the free ends of the arms, a dipper carried by the free ends of the sticks, a sheave-carrying arm pivotally mounted centrally of and in the base of the A-frames, a line for raising and lowering the dipper leading over the sheave in said last mentioned arm and over one and intermediate of the two first mentioned sheaves, means for swinging the free ends of the pendulum arms for crowding the dipper to its work and assisting in discharging same, a cross bar transverse one end of the A-frame sup-

port and fixed upon the inclined edges of same, a bumper frame pivoted in the A-frames below the cross bar and impinging the latter when upright, contractive spiral springs holding the upper end of the bumper frame toward the upper end of the A-frames and means projecting beyond the side walls of the dipper for engaging the bumper substantially as and for the purpose described.

8. The combination with a mechanical shovel of the character described, comprising a suitable pivotal support, a dipper pivotally carried by the support and operated thereover and a single line for raising and lowering the dipper upon either side of the support, of means controlled by the mechanism which operates the dipper for automatically changing the direction of draft of said line.

9. The combination with a mechanical shovel comprising a vertically disposed pivoted support, depending arms pivoted on the outside of the upper portion of the support, a dipper pivotally carried upon the free ends of the arms and operative over the support and means for operating the dipper, of means for reciprocating the free ends of the arms independently of the other operating means.

10. The combination with a structure as described in claim 4, of the dipper sticks arched upwardly, substantially as and for the purpose described.

11. The combination with a mechanical shovel of the character described, comprising a suitable upright support, one piece dipper arms pivotally and reciprocally carried by the support and a dipper carried on the free ends of the arms and operative over the support, of a single operating line leading through the upper end of the support and operating the dipper and its arms over the support.

In testimony whereof I hereunto affix my signature in the presence of two witnesses.

FRED LERCH.
